US00D770273S

(12) **United States Design Patent** (10) **Patent No.:** **US D770,273 S**
Fife et al. (45) **Date of Patent:** **** Nov. 1, 2016**

(54) **CONTAINER**

- (71) Applicant: **Peninsula Packaging, LLC**, Exeter, CA (US)
- (72) Inventors: **Chadrick Paul Fife**, Yakima, WA (US); **John David Perry**, Naches, WA (US)
- (73) Assignee: **PENINSULA PACKAGING, LLC**, Exeter, CA (US)
- (**) Term: **15 Years**
- (21) Appl. No.: **29/531,666**
- (22) Filed: **Jun. 29, 2015**

Related U.S. Application Data

- (62) Division of application No. 29/493,608, filed on Jun. 11, 2014, now Pat. No. Des. 743,784.

Primary Examiner — Karen S Acker*Assistant Examiner* — Wendy Arminio(74) *Attorney, Agent, or Firm* — Loza & Loza, LLP; Heidi L. Eisenhut(57) **CLAIM**

The ornamental design for a container, as shown and described.

DESCRIPTION

FIG. 1 is a front top left perspective view of a container of the present invention;

FIG. 2 is a bottom rear right perspective view of the container of FIG. 1;

FIG. 3 is a front elevation view of the container of FIG. 1;

FIG. 4 is a rear elevation view of the container of FIG. 1; FIG. 5 is a left side elevation view of the container of FIG. 1;

FIG. 6 is a right side elevation view of the container of FIG. 1;

FIG. 7 is a top plan view of the container of FIG. 1; and, FIG. 8 is a bottom plan view of the container of FIG. 1.
